UNITED STATES PATENT OFFICE.

CLARENCE T. McDONALD, OF CHICAGO, ILLINOIS, ASSIGNOR TO MULTI REFILLABLE FUSE COMPANY, OF CHICAGO, ILLINOIS, A CORPORATION OF ILLINOIS.

REFILLABLE CARTRIDGE-FUSE.

1,311,661.

Specification of Letters Patent. Patented July 29, 1919.

Application filed May 28, 1917. Serial No. 171,356.

To all whom it may concern:

Be it known that I, CLARENCE T. McDONALD, a citizen of the United States, residing at Chicago, in the county of Cook and State of Illinois, have invented certain new and useful Improvements in Refillable Cartridge-Fuses, of which the following is a specification.

This invention relates to inclosed or cartridge fuses of the refillable type, wherein the fusible element is removably mounted in its casing so that the fuse element may be renewed or replaced by another when disrupted.

15 One of the objects of the invention is to provide improved means for securing the fuse terminals to the ends of the tubular casing, and the invention refers more particularly to a fuse of the blade-terminal type

20 and to the means for rigidly securing the blades against lateral longitudinal or rotational movement.

Another object is to provide a construction arranged to prevent the escape of flame along the terminals when the fuse is disrupted.

In the drawings, Figure 1 is a longitudinal central sectional view of a blade type of fuse embodying my invention. Fig. 2 is 30 a similar view of one end of the fuse taken in a plane at right angles to Fig. 1 and on line 2—2 thereof. Fig. 3 is a transverse sectional view taken on line 3—3 of Fig. 1. Fig. 4 is a detail side view of one of the terminal blades and its packing sleeve. Fig. 5 is a detail view of the improved locking washer employed.

A hollow cylindrical sleeve or shell 10 of non-conducting and non-inflammable material is provided at its ends with suitable means for immovably holding a unitary fuse device therein. Herein I have shown said unitary fuse device as composed of the knife-blade terminals 11 and the fusible element 12 detachably secured together by suitable means such as the bolts 13, nuts 14 and washers 15. Upon each end of the shell 10 is suitably and rigidly secured a tubular head 16 provided with opposed, transverse, inwardly-extending segmental webs 17. The webs at opposite ends of the shell are alined with each other. The fuse element with

the attached terminals is passable longitudinally through the shell and ferrules, and, when centrally positioned, may be rotated 55 to bring shoulders 18 formed on the terminals 11 into engagement with the outer faces of the webs 17. The unitary fuse device is thus locked against longitudinal movement in the shell, as long as the fusible 60 element 12 remains intact.

To lock the fuse device against rotation, I provide the following means: A washer 19, suitably slotted as at 20, non-rotatably engages the terminal blade 11 and is slidable 65 thereon. Upon one face of the washer are formed or otherwise secured abutments or bosses 21. These bosses are so positioned that when the washer is seated against the head 16 or the webs 17 the bosses engage the 70 edges of the projecting webs 17 to lock the washer as well as the terminal blade and fuse element against lateral movement or rotation. To secure the before-mentioned parts in place, an annular end cap 22 is 75 provided which passes around the terminal blade and is suitably secured to the head 16 or shell 10. Herein I have shown the end cap screwed upon the head, thereby clamping the locking washer between the head and 80 the end cap.

Upon each terminal blade 11 is formed or suitably secured an encircling flange or sleeve 23, best seen in Figs. 2 and 4, and which is adjacent to the washer 19. Between 85 the said sleeve and washer is provided non-inflammable packing material 24 which is compressed to form a gas-tight joint about the slot 20 when said end cap is screwed down upon the ferrule and engages said 90 washer. This construction prevents the escape of flame along the terminal blade when the fuse element is disrupted. The flange 23 also constitutes an abutment to coöperate with the washer 19 in preventing outward 95 longitudinal movement of the blade.

So long as the fuse element remains whole, the shoulders 18 on the blades coöperating with the webs 17 on the heads prevent longitudinal movement of both blades, but 100 when the fuse element blows the blades could slide outward if it were not for the flange 23 or equivalent form of abutment on the blade.

While I have herein described in considerable detail the preferred embodiment of my invention, I would have it understood that I do not thereby intend to limit myself 5 to the form disclosed since many modifications will be readily apparent to those skilled in the art. The scope of the invention will be pointed out in the appended claims.

10 I claim as my invention:

1. A refillable cartridge fuse having in combination, a tubular shell, an inwardly projecting transversely disposed web rigidly secured to an end of said shell, a unitary 15 fuse device extending through said shell and having a portion directly engaging said web, a washer, an abutment on said washer engaging the inner edge of said web to hold the washer against rotation with relation to 20 the shell, and means to secure all of said parts together.

2. A refillable cartridge fuse having, in combination, a tubular shell, an inwardly projecting transversely disposed web secured 25 to an end of said shell, a unitary fuse device extending through said shell and having a portion directly engaging said web, a washer slidable upon said fuse device, packing means on said fuse device coöperating 30 with said washer to form a gas-tight joint, and means to secure all of said parts together.

3. A refillable cartridge fuse having, in combination, a tubular shell, a unitary fuse 35 device extending through said shell, a slotted washer secured to the shell in direct engagement with the end thereof and embracing said fuse device, an abutment fixedly secured to said fuse device, packing material 40 between said washer and said abutment, and an end cap to secure all of said parts together.

4. A refillable cartridge fuse having, in combination, a tubular shell, a pair of oppositely positioned and inwardly projecting 45 transversely disposed webs secured thereto, a unitary fuse device extending through the shell and having cut-away portions for direct engagement with said webs, a washer embracing said fuse device, bosses on the washer engaging the inner edges of said webs, and means to secure all of said parts together.

5. A refillable cartridge fuse having, in combination, a tubular shell, an inwardly projecting transversely disposed web secured thereto, a unitary fuse device extending through the shell and comprising a fusible 55 element and a terminal detachably secured to said element, said terminal having a cut-away portion for engagement with said web, a washer embracing said terminal, a boss on said washer engaging the inner edge of said web, and means to secure all of said parts 60 together.

6. A refillable cartridge fuse having, in combination, a tubular shell, an inwardly projecting transversely disposed web secured thereto, a unitary fuse device extending through the shell and comprising a fusible 70 element and a terminal detachably secured to said element, said terminal having a cut-away portion for engagement with said web, a washer embracing said terminal, bosses on said washer engaging said web, means 75 fixedly secured to said terminal, packing means adjacent said last mentioned means, and means to secure all of said parts together.

7. A refillable cartridge fuse having, in combination, a tubular shell, a tubular head rigidly secured to an end of said shell, an inwardly projecting transversely disposed web rigid with said head, a fuse terminal blade extending through said head and having a portion directly engaging said web, a washer slotted to receive said blade, an abutment on said washer to coöperate with the inner edge of said web in holding said washer against rotation with relation to said 90 shell, and means to secure all of said parts together.

8. A refillable cartridge fuse having, in combination, a tubular shell, a transverse web at one end thereof, a fuse terminal blade 95 extending through said shell and having a portion to abut directly against said web, a slotted washer slidable upon said blade and having an interlocking engagement with said web, packing means adjacent said 100 washer and surrounding the joint between said washer and said blade, and means to secure all of said parts together and compress said packing material.

9. A refillable cartridge fuse having, in combination, a tubular shell, a segmental web at the end thereof, a unitary fuse device extending through said shell, an apertured washer receiving said fuse device and engaging the inner edge of said web, packing 110 means adjacent said washer and surrounding the joint between said washer and said fuse device, and an end cap to secure all of said parts together and compress said packing means.

10. A refillable cartridge fuse comprising, in combination, a rigid tubular body, an apertured washer closing one end of the body, a terminal passing through the aperture in said washer and having shoulders adapted to directly engage the end of said body to limit inward movement of said terminal, means on said terminal coöperating with said washer to limit outward movement of the terminal, and means for securing said washer to the body.

11. A refillable cartridge fuse comprising, in combination, an insulating sleeve, a tubular metallic head fixed on one end of said sleeve, a slotted washer closing one end of

said head and sleeve, means to prevent relative rotation of the washer and head, a terminal blade passing through the slot in said washer and having shoulders arranged to abut against the outer end of said head to limit inward movement of said blade, means on said blade arranged to engage said washer to limit outward movement of said blade, and a cap surrounding said washer and threaded upon said head for clamping the washer and the terminal blade tightly in place.

12. A refillable cartridge fuse comprising, in combination, an insulating sleeve, a tubular metallic head fixed on one end thereof, the interior of the head at the outer end thereof being of irregular or non-circular shape, an apertured washer closing the outer end of said head and having means conforming to the irregularity of said interior of the head, whereby to prevent relative rotation of the washer and the head, a terminal passing through the aperture in said washer, means for preventing longitudinal movement of the terminal, and means for securing the washer to the head.

13. A refillable cartridge fuse comprising, in combination, a tubular body portion, a single washer positioned across one end thereof, a terminal blade passing through said washer, means on said blade to engage said body portion to limit longitudinal movement of the blade in one direction, means fixed on said blade to engage said washer to limit longitudinal movement of the blade in the opposite direction, means for preventing relative rotary movement between the washer and the body portion, and means for securing said washer to the body portion.

14. A refillable cartridge fuse comprising, in combination, an insulating sleeve having a pair of metallic heads fixed on opposite ends thereof and provided with irregularly shaped openings, a unitary fuse device comprising a pair of terminal blades joined by a fusible section detachably secured to said blades, said blades and fusible section being insertible as a unit through said sleeve and heads and being then rotatable to cause parts on said blades and said heads to interlock to prevent longitudinal movement of said unitary device, and means for securing the blades to the respective heads in such interlocked position.

15. A refillable cartridge fuse comprising, in combination, an insulating sleeve having a pair of tubular metallic heads fixed on its ends, a unitary fuse device comprising two terminal blades joined by a fusible section, said device being insertible longitudinally through said sleeve and heads, said blades having shoulders and said heads having inwardly extending webs into engagement with which said shoulders may be

brought by rotating the unitary fuse device on its longitudinal axis within the sleeve, means comprising slotted washers through which said blades extend for preventing rotation of said blades out of engagement with said webs, and caps surrounding said blades and threaded on said heads for securing said washers in blade-holding positions.

16. A refillable cartridge fuse comprising, in combination, a tubular body, a terminal projecting from one end thereof, means surrounding said terminal for clamping it to the body in fixed position, and means carried solely by said terminal for preventing the escape of gas or flame around the surface of said terminal.

17. A refillable cartridge fuse comprising, in combination, a tubular body, a terminal blade, a slotted washer through which said blade extends, means for preventing rotation of said washer, means for securing said washer to the body, and packing means carried solely by said terminal blade surrounding the blade adjacent to the slot in said washer and arranged to prevent the escape of gas or flame through the slot.

18. A refillable cartridge fuse comprising, in combination, a tubular body, a terminal blade, a slotted washer through which said blade extends, means for preventing rotation of said washer, means for securing said washer to the body, a continuous ledge fixed on the blade at the inner side of said washer, and packing material between said ledge and said washer arranged to prevent escape of gas or flame through the slot in the washer.

19. In an inclosed cartridge fuse, a rigid tubular body having an open end, and a washer for closing said open end having a central elongated slot to receive a terminal blade and having on one of its side faces a plurality of projections spaced inwardly from the periphery of the washer, the tubular body being shaped to coöperate with said projections to hold the washer against rotation relative thereto.

20. In an inclosed electric fuse, a knife blade having a portion at one edge cut away to provide a stop shoulder and having an abutment or projection spaced inwardly from said shoulder a sufficient distance to permit packing material to occupy the space between the plane of the shoulder and the plane of the abutment.

21. A refillable cartridge fuse having, in combination, an insulating sleeve, a tubular metallic head on each end of said sleeve and provided with an inwardly projecting web, a unitary fuse device comprising a pair of terminal blades joined by a fusible section and each having a shoulder directly engaging the webs in the respective heads, a slotted washer surrounding each of said

terminals, and means for clamping said washers in position on the ends of the heads.

22. In an inclosed electric fuse, an insulating sleeve, a tubular metallic head on the end of said sleeve having an inwardly projecting web, a unitary fuse device, and means for holding said fuse device when

in one position in abutting engagement only with said web, said device being when in another position movable through the head 10 past said web.

In testimony whereof, I have hereunto set my hand.

CLARENCE T. McDONALD.
